UNITED STATES PATENT OFFICE.

ARTHUR C. CANDLAND, OF PROVO, UTAH.

RAILWAY-RAIL FASTENER.

1,025,453.

Specification of Letters Patent.

Patented May 7, 1912.

Application filed December 9, 1911. Serial No. 664,877.

To all whom it may concern:

Be it known that I, ARTHUR C. CANDLAND, a citizen of the United States, residing at Provo city, in the county of Utah and State 5 of Utah, have invented certain new and useful Improvements in Railway-Rail Fasteners, of which the following is a specification.

The present invention relates to railway 10 ties and means to fasten the rails thereon, and my purpose is to provide a device that will hold the rails on a metallic tie at any desired point in the longitudinal length thereof.

15 A further object is to provide a fastening means having the minimum number of parts to secure the rails on the simplest form of metal ties and which may be assembled within the least time.

20 These objects I accomplish with the device illustrated in the accompanying drawings in which similar letters of reference indicate like parts throughout the several figures.

25 Figure 1 is a perspective of one end of a metal tie with my fastening means securing a part of a rail thereon. Fig. 2 is a plan view of one end of a metal tie with the reinforcing member therein. Fig. 3 is a perspective of said reinforcing member. Fig. 4 is a vertical section on line $z-z$ of Fig. 5. Fig. 5 is a transverse vertical section cutting the rail longitudinally. Fig. 6 is a perspective of one of the clamps. Fig. 7 is 35 a perspective of one of the cushion blocks.

Within the metal tie 1 of an upturned channel shape, is secured reinforcing members 2, having a portion of the sides thereof formed into locking cylinders 3. Another 40 portion of the sides of said reinforcing members 2 is not so bent, but is left upstanding to form lugs 4 against which the clamps 6 engage to prevent outward lateral movement. Except where the rails may be closer together as at switches the said members 2 may be riveted within said channel 1. At places where the rails may be placed closer than the standard width and where more than two rails are carried on a tie the said 45 members 2 are adjustably secured in said channel 1. Within each of said reinforcing members 2 is fitted a cushion block 5, on which the rails are to be placed. These blocks are made of wood or fibrous material 50 and supply under the rails the resiliency or cushion effect desired. Adjacent said blocks

5 and on each end of each of them is fitted one of the clamps 6, portions thereof bearing against the said upstanding lugs 4 to prevent the clamps from spreading apart. 60 Each of said clamps has open slots 7 cut therein to allow the sides of said channel 1 to engage therein, and the outer portions 8 of said clamps lock the sides of said channel against outward displacement. Said portions 8 have ballast placed against the sides thereof which prevents lateral movement of the ties. Within said portions 8 of said clamps are cut elongated openings 9, partially registering with the said locking cylinders 3. Within said openings 9 of one of said clamps and through said cylinders 3 are fitted threaded bolts 10 having a cone shaped head on each. On each of said bolts 10 and within the said elongated openings 9 65 of the opposite clamp is fitted a frustoconically shaped nut 11 portions of which extend into the other end of said cylinders 3. The purpose being that when said nuts are turned in on said bolts the said cone shaped head and cone shaped nut will press down on the said clamps and against the top of the inner side of said cylinders and in that way draw the portion 12 of said clamps 70 down on the base flange of the rail. 75

I am aware of the fact that others have used and patented metallic ties of the channel shape but so far as known to me none have provided as simple and efficient means for fastening the rails on the tie as shown 80 and described herein, and especially wherein the fastening means may be adjusted to the different positions on the tie wherein rails may be secured. The feature of the down-turned and inward pull of the rail engaging 85 clamps as they grip the flange of the rail with the minimum number of parts is certainly novel.

Having thus described my device I desire to secure by Letters Patent and claim:—

1. A railway fastener consisting of reinforcing members adjustably secured within an upturned channel, cushion blocks within said reinforcing members, clamps in said reinforcing members a portion adapted to 100 grip the base flange of a rail supported by said blocks and another portion extended to lock the sides of said channel from outward movement, elongated circular openings in said clamps, locking cylinders integrally 105 formed on the sides of said reinforcing members with the openings therethrough par-

ually registering with the said elongated openings in said clamps, and a locking bolt having a cone shaped head and a cone shaped nut thereon passing through said elongated openings and said locking cylinders and tending to draw said clamps downward and toward each other.

2. A railway fastener consisting of reinforcing members adjustably secured within 10 an upturned metal channel, lugs extending above the sides of said channel integrally formed on the edges of said reinforcing members, cushion blocks in said reinforcing members, clamps transversely fitted in said reinforcing members adapted to grip the base flange of a rail supported on said blocks, an extended portion on each end of each clamp adapted to lock the sides of said channel against outward movement and having 15 an elongated opening therein, locking cylinders integrally formed on the upper edges of said reinforcing members and between said lugs with the opening through said cylinders partially registering with the 20 elongated openings in said clamps, bolts each having a cone shaped head placed through each of said cylinders with the head in the elongated openings in said clamps, and a frusto-conically shaped nut on said 25 bolt in the elongated opening of the opposed clamp adapted to draw the said clamps downward and inward in gripping contact with said rail.

3. A railway fastener consisting of reinforcing members adjustably secured within 30 an upturned metal channel, clamps transversely placed in said reinforcing members adapted to grip the base flange of a railway rail, and means to draw said clamps downward in said reinforcing members and inward to grip the base flange of said rail.

4. A railway fastener consisting of reinforcing members adjustably secured within 35 an upturned metal channel, cushion blocks carried in said reinforcing members, clamps transversely placed in said reinforcing mem-

bers adjacent said blocks and adapted to grip the base flange of a railway rail, and means to draw said clamps downward and toward each other in pairs to grip the base 50 flange of a rail.

5. A railway fastener consisting of reinforcing members adjustably secured within an upturned metal channel, cushion blocks carried in said reinforcing members, clamps 55 transversely placed in said reinforcing members adjacent said blocks and adapted to grip the base flange of a railway rail, locking cylinders integrally formed on the edges of said reinforcing members, and a locking 60 bolt having a cone shaped head and a cone shaped nut thereon passing through said clamps and each of said locking cylinders tending to draw said clamps downward and toward each other in pairs to grip the base 65 flange of a railway rail.

6. A railway fastener consisting of a metal channel, reinforcing members adjustably secured within said channel, upstanding lugs integrally formed on the sides 70 of said reinforcing members, locking cylinders formed by bending other portions of the sides of said reinforcing members, blocks carried in said reinforcing members, clamps transversely placed in said reinforcing 75 members and adjacent said blocks and adapted by placing them in pairs to grip the base flange of a rail, and having elongated openings in each, and a locking bolt having a cone shaped head and a cone 80 shaped nut thereon passing through said clamps and each of said locking cylinders adapted to draw said clamps downward and toward each other in pairs to grip the base 85 flange of a rail.

In testimony whereof I have affixed my signature in presence of two witnesses.

ARTHUR C. CANDLAND.
